TOY GUN

Gerard Rauglas, Aroma Park, Ill.

Filed Mar. 6, 1957, Ser. No. 644,327

8 Claims. (Cl. 124—14)

This invention relates to a toy gun construction, and more particularly to a pop-gun construction embodying numerous safety features and, at the same time, maintaining a highly realistic appearance.

Various pop-guns have heretofore been proposed which, however, by reason of design, are beset with one or more shortcomings. For example, in many instances a projectile, normally cork, is utilized, which is expelled from the forward end of the barrel upon firing of the gun and, thus, is a potential hazard to person or property when the gun is carelessly handled. In addition, the projectile is susceptible to being lost and, in certain instances, makes reloading of the gun an awkward operation, particularly for small children. A second shortcoming, which is prevalent in most prior art guns of this type, is the awkwardness, difficulty, and delay experienced, particularly by small children, in cocking the gun prior to firing. Third, there is a real danger in many prior guns, of a child's finger or hand becoming accidentally caught in the cocking or trigger mechanism during firing of the gun. Fourth, prior guns are normally not capable of being readily assembled and disassembled by a child. Lastly, prior pop-guns frequently have the various operating parts thereof of a delicate and complex construction and not readily capable of withstanding abusive handling.

Thus, it is one of the objects of this invention to provide a toy gun construction which is not beset with the aforementioned shortcomings.

It is a further object of this invention to provide a toy gun which is highly realistic in appearance and is not a potential hazard when in inexperienced hands.

It is a further object of this invention to provide a toy gun which enables a child to readily cock the gun without the latter being removed from a firing position.

It is a still further object of this invention to provide a toy gun where accidental firing of the gun cannot occur until the cocking mechanism is returned to its proper starting position, thereby simulating the motion required in firing certain military or hunting weapons.

It is a still further object of this invention to provide a toy gun which is readily capable of assembly and disassembly and, thus, is of educational value to a child as well as providing an interesting and enjoyable means of improving the adroitness of the child.

It is a still further object of this invention to provide a toy gun which is of simple and durable construction, inexpensive to produce, and effective in operation.

Further and additional objects will appear from the description, accompanying drawings and appended claims.

In accordance with one embodiment of this invention, a toy gun is provided which includes an elongated barrel having the forward end thereof closed and an apertured abutment disposed within such barrel and spaced a predetermined distance from such end to form an elongated chamber. Mounted for reciprocatory movement within the barrel is a slide member. The slide member is dis-

2

posed rearwardly of the apertured abutment and is adapted to entrap and compress a fluid rearwardly of such abutment. Disposed within the elongated chamber is an element which is adapted to be moved into seating engagement with the abutment aperture upon rearward relative movement of the slide member. The element is responsive to the compressed fluid and is adapted to be moved from its seated position into the chamber independently of the slide member. The movement of the element within the chamber is guided by means of an elongated guide piece extending rearwardly from the element through the abutment aperture and terminating in a sliding engagement within the slide member.

For a more complete understanding of this invention, reference should be made to the drawing, wherein:

Figure 1 is a side elevational view of one form of the improved gun;

Fig. 2 is a bottom view of Fig. 1;

Fig. 3 is an enlarged fragmentary sectional view taken along line 3—3 of Fig 2;

Fig. 4 is an enlarged fragmentary sectional view of Fig. 3, showing the firing mechanism in a changed position;

Fig. 5 is an exploded perspective view of the firing mechanism; and

Fig. 6 is an enlarged fragmentary perspective view of the rear end of the barrel of a modified form of the improved gun.

Referring now to the drawing, an improved pop-gun 10 is shown which, in this instance, is in the form of a rifle, and comprises a barrel 11 and stock or shoulder-engaging portion 12. The barrel 11, as seen more clearly in Fig. 3, includes an elongated tubular front section 13 which projects forwardly of the stock 12, and an elongated relatively short tubular rear section 14 which is adapted to encompass a portion of the rear end of section 13.

Slidably disposed within rear section 14 is the firing mechanism 15. The forward movement of firing mechanism 15 within the barrel is controlled by a trigger mechanism 16, which is mounted within stock 12.

Disposed at the front end of barrel section 13 is a plug-like element 17 which is adapted to close off the end of the barrel. Spaced rearwardly from element 17, and mounted in fixed relation within the barrel interior, is a first abutment 18. The spacing between element 17 and abutment 18 forms a first or projectile chamber, the purpose of which will be described more fully hereinafter. Spaced rearwardly from first abutment 18, and mounted in fixed relation within the barrel interior and adjacent the rear end thereof, is a second abutment 20. The spacing or chamber 21, disposed between the first and second abutments is adapted to accommodate an elongated rod 31 which is integrally connected to firing mechanism 15. Affixed to the rear end of second barrel section 14 is a plug-like element 22. The spacing or chamber 23 formed between the second and third abutments is adapted to accommodate the firing mechanism 15.

Disposed within the first chamber 19 is projectile element 24, preferably formed of a cork material. The movement of element 24 is confined to within chamber 19 and thus prevents the projectile element injuring person or property, or becoming lost. Element 24, when moved rearwardly relative to the barrel, in a manner to be described more fully hereinafter, is adapted to become seated within tapered bore 25 formed in abutment 18. To effect this rearward movement, element 24 has extending therefrom an elongated stem 26 which passes through bore 25 and has the rear end 27 thereof terminating within an elongated cavity 28 formed in forward end 30 of rod 31. Rod 31, in turn, extends through and

is guided by a suitable bore 40 formed in second abutment 20. The rear end of rod 31 terminates in a firing head 43, which forms a part of firing mechanism 15 and is slidably disposed in chamber 23.

Affixed to plug-like element 17, and projecting into chamber 19, is a cushion piece 32, which is adapted to cushion the shock of element 24 when it is discharged from the abutment aperture 25 into chamber 19. Formed in the portion of barrel section 11 encompassing chamber 19 are a plurality of apertures 33 (see Figs. 1 and 2) which are provided to permit the noise, caused when the element 24 is discharged into chamber 19, to readily escape and produce the desired "pop" when the gun is fired. The number and size of apertures 33 may be varied so that the desired pop sound may be obtained. Affixed to the outer periphery of cavitated rod portion 30 is a plunger 34, formed of a plurality of washer-like elements 34a arranged in abutting side-by-side relation. The outer periphery of each element 34a slidably engages the interior surface of the barrel chamber 21. Secured to the front end of portion 30 and disposed forwardly of plunger 34 is a guide piece 35 which is provided with a suitable central opening to permit the stem 26 to slidably extend into cavity 28. The rear end 27 of stem 26 is enlarged and impassable through the opening in piece 35 and, thus, accidental disengagement of rod 31 and stem 26 is prevented. The longitudinal dimension of stem 26 is such that, when rod 31 is moved rearwardly relative to the barrel 11 by the firing mechanism 15, enlarged end 27 will be engaged by guide element 35 and move rearwardly with the rod 31 whereby element 24 will become firmly seated within the aperture 25 formed in abutment 18.

A small breather hole 36 (see Fig. 2) is formed in the portion of the barrel section 13 encompassing chamber 21, so as to release any vacuum created within the barrel when the plunger 34 is drawn rearwardly during cocking of the gun. Element 24 is unseated from aperture 25 by compression of the air, rearwardly of abutment 18, effected by forward movement of the plunger 34 within barrel chamber 21. Forward movement of plunger 34 is controlled by the trigger mechanism 16 operating on firing mechanism 15. It is the sudden expelling of projectile element 24 into chamber 19 which produces the desired pop.

Rod 31 is centrally aligned within barrel section 13 and has affixed thereto, a short distance rearwardly of end portion 30, a shoulder 37. Shoulder 37 contacts the forward end of a coil spring 38 which encompasses the rod 31 and is disposed between second abutment 20 and shoulder 37. It is the energy of spring 38, when the firing mechanism is released by trigger mechanism 16, which impeis the firing mechanism and plunger 34 in a forward direction within barrel 11. The rod 31 is maintained in substantial axial alignment with the axis of the barrel 11 by the plunger 34 affixed thereto and the central bore 40 formed in second abutment 20. Abutment 20 is maintained in a fixed position within the barrel 11 by a removable bolt 41, which is mounted within the stock 12 and threaded into the underside of abutment 20.

Firing mechanism 15 includes, in addition to rod 31 and firing head 43, a cocking member 42 which is provided with a bore through which a portion of rod 31 slidably extends. Member 42 is disposed between firing head 43 and abutment 20 and is adapted to cause head 43 to be withdrawn in chamber 23 until it is in cocked position C (see Fig. 4). Member 42 is manually actuated by a laterally extending arm 44, which extends through an elongated slot 45 formed in the periphery of barrel section 14.

Firing head 43 is retained in its cocked position C (see Fig. 4) by an upwardly projecting portion 46 formed on a lever 47 (see Fig. 5) of the trigger mechanism 16. The operation of lever 47 and the remainder of trigger mechanism 16 will be described more fully

hereinafter. Threadably mounted on plug-like element 22, and extending axially into the rear of chamber 23, is a stop adjustment 48 which is adapted to limit the extent to which the firing head 43 may be withdrawn relative to barrel 11. The purpose of having stop element 48 adjustable is to insure that the rearward movement of firing head 43 and rod 31 will be sufficient to positively seat projectile element 24 within aperture 25 of abutment 18. After prolonged firing of the gun, the element 24, because of its resilient character, becomes slightly worn, thereby necessitating the element 24 to be withdrawn further into tapered bore 25. Plug element 22 is retained in a relatively fixed position at the rear end of barrel section 14 by a removable bolt 50 carried by the stock 12.

The trigger mechanism 16, which is shown more clearly in Fig. 5, includes, in addition to lever 47, a finger piece 51, in the form of a bell-crank lever, which is pivotally mounted within a suitable recess 49, formed in stock 12. Piece 51 has a nose portion 51a which is disposed within a suitable cut-out 47a formed in the rearwardly disposed end of lever 47. Piece 51 also has a depending secbnd portion 51b which projects from beneath stock 12 and is adapted for finger engagement. Projecting upwardly a slight amount from the juncture of portions 51a and 51b of piece 51 is a lug 51c. Piece 51 pivots about a pin 52, which is carried by stock 12. The upper protruding end 46 of lever 47 extends through a suitable elongated groove formed in the underside of barrel section 14, so that end 46 will interrupt forward movement of firing head 43 and retain the latter in cocked position C, as seen more clearly in Fig. 4. The rear end 46 of lever 47 is spaced from lug 51c, as seen more clearly in Fig. 5.

Disposed adjacent to, and to one side of, lever 47 is an elongated safety lever 53. Levers 47 and 53 are adapted to pivot about a common pin 54, which is mounted within stock 12. The rear end of lever 53, that is, the end adjacent piece 51, is provided with an offset portion 53a, which is adapted to be disposed within the spacing between the end 46 of lever 47 and lug 51c formed on piece 51. Offset portion 53a is adapted to prevent pivoting movement of piece 51 in a clockwise direction about pin 52 as an axis, when lever 53 is pivoted its fullest extent in a counter-clockwise direction about pin 54 (see Figs. 3 or 4). Lever 53 is biased to assume this latter position by reason of spring 56, carried within a suitable pocket 12b formed in stock 12.

Disposed to the opposite side of lever 47 is a spacer 50 lever 55 which, likewise, is adapted to pivot about pin 54. Levers 47, 53 and 55 are all disposed within a portion of recess 49, formed in stock 12. Lever 47 is biased in a clockwise direction about pin 54 by spring 47b, the lower end of which is disposed within a suitable pocket 12a formed in stock 12. As previously mentioned, safety lever 53 is also biased in a counter-clockwise direction by spring 56, the lower end of which is disposed within a suitable pocket 12b formed in stock 12.

The end 53b of lever 53, opposite from offset end 53a projects upwardly through the elongated slot formed in the underside of barrel section 14, into the chamber 23 (see Fig. 4) by reason of spring 56. When cocking member 42 is in its most forward position, that is, when firing head 43 is in position B, end 53b of lever 53 is depressed, whereby offset end 53a is moved out of the way of lug 51c of trigger piece 51 to permit the latter to pivot in a clockwise direction and, in turn, depress the end 46 of lever 47 out of the way of firing head 43. When head 43 is moved rearwardly into cocked position C by member 42, end 53b of lever 53 is free to project into chamber 23 and, simultaneously therewith, prevent pivoting of trigger piece 51. Lever end 53b remains in its raised position until cocking member 42 is returned to its forwardmost position against abutment 20. Thus, before firing the gun, it is essential that cocking member 42 is

in its correct position. Cocking member 42 has the underside thereof provided with a cut-out 42a, which is adapted to accommodate the projecting portion 46 of lever 47 without depressing same, when member 42 moves rearwardly to cock the gun.

In Fig. 6 is shown a modified form of barrel section 14 in which is disposed a safety sleeve 57, which is substantially cylindrical in shape and one side thereof provided with an elongated slot 58. Sleeve 57 is disposed within chamber 23 intermediate the second abutment 20 and end member 22. The slot 58 is adapted to permit the cocking arm 44 to extend therethrough. Sleeve 57 is adapted to turn about its longitudinal axis by cocking arm 44 when the latter is moved into and out of offset portion 45a of slot 45 formed in barrel section 14 (see Fig. 6). At opposite ends of slot 58 there are formed cut-outs 58a, one to accommodate end 46 of lever 47 and the other end 53b of lever 53, when sleeve 57 is turned about its longitudinal axis. When cocking arm 44 is disposed in slot portion 45a, the sleeve 57 will close off elongated slot 45 and thereby prevent the user of the gun becoming injured, or the gun damaged, by placing fingers or foreign matter into chamber 23, before the firing head 43 is moved from its cocked position. The inner diameter of sleeve 57 is such as to permit firing head 43 and cocking member 42 to slide therein.

In Fig. 3 the plunger 34 is shown in dotted lines at a position A, which is the position it assumes when the firing head 43 is in its cocked position C. Thus, the distance plunger 34 moves rearwardly relative to barrel section 13 to position A is greater than the extent to which stem 26 extends into cavity 28 formed in rod end 30 and, thus, seating of element 24 in aperture 25 is assured.

While the improved pop-gun construction is shown incorporated within a rifle type of gun, it is to be understood, of course, that such mechanism might be incorporated in guns of other types than that shown. The advantages of utilizing arm 44 to cock the firing head 43 is such that one may readily cock the same without removing the gun from his or her shoulder and, thus, cause more rapid firing, with little or no awkwardness. The size and stiffness of spring 38 may be varied to suit the capabilities of the user of the gun.

By reason of removable bolts 50 and 41, the barrel 11 may be readily disassembled from stock 12. In addition, end member 22 may be withdrawn from the barrel, as well as head 43 and cocking member 42, subsequent to arm 44 being removed from the latter. Head 43 may be disconnected from rod 31 by removing a screw 60, which is axially threaded into the end of rod 31. The enlarged head of the screw is disposed in a countersunk opening formed in the rear face of head 43.

Thus, it will be seen that a pop-gun construction has been provided which is possessed of numerous safety features not heretofore possessed by the prior art. In addition, the improved gun is highly realistic in appearance. The improved gun may be readily disassembled by young and old alike and thus enables the young to improve their adroitness and, at the same time, provides a source of knowledge of proper gun care, as well as great enjoyment.

While several embodiments of this invention are shown above, it will be understood, of course, that the invention is not to be limited thereto, since may modifications may be made, and it is contemplated, therefore, by the appended claims, to cover any such modifications as fall within the true spirit and scope of this invention.

I claim:

1. A toy gun comprising an elongated barrel having the forward end thereof closed, an apertured first abutment disposed within said barrel and spaced rearwardly from said closed forward end, a second abutment disposed within said barrel and spaced rearwardly from said first abutment, means mounted for reciprocatory movement within said barrel, said means having a first por-

tion thereof of said intermediate said abutments for entrapping and compressing a fluid between said first abutment and said first portion, and a second portion thereof of said second abutment, said means being biased for movement in a forward direction, a cocking unit mounted for engagement with said means for actuating the latter rearwardly to a cocked position wherein the second portion of said means is spaced a predetermined distance from said second abutment, an element disposed within said barrel intermediate said first abutment and said closed forward end, said element being operatively connected to said means upon rearward movement thereof and effecting a seating engagement within the aperture of said first abutment, said element being responsive into an unseated position by the fluid compressed by said means first portion, the movement of said element within said barrel being along a substantially guided path, a trigger means mounted for releasable engagement with said means second portion to retain the latter in said cocked position.

2. A top gun comprising an elongated barrel having the forward end thereof closed, an apertured first abutment disposed within said barrel and spaced a predetermined distance from said closed forward end to form a chamber, the portion of said barrel defining said chamber being provided with an opening, an apertured second abutment disposed within said barrel and spaced rearwardly a substantial distance from said first abutment, a slide member mounted for reciprocatory movement within said barrel, said slide member being biased for movement in a forward direction relative to said barrel and having integrally connected first and second portions, said first portion being disposed intermediate said abutments and provided with a head-piece, disposed adjacent said first abutment, for entrapping and compressing a fluid intermediate said first abutment and said head, said first portion being provided with a longitudinal bore opening adjacent said first abutment, the second portion of said slide member being disposed rearwardly of said second abutment, a cocking unit mounted for engagement with said slide member second portion to actuate the latter rearwardly into a cocked position wherein the end of the second portion of said slide member is spaced a predetermined distance from said second abutment, an element disposed within said chamber and actuated by said slide member into seating engagement within the aperture of said first abutment wherein said aperture is closed off, upon movement of said slide member into said cocked position, said element, when in said seating engagement, being responsive to the fluid compressed by said slide member and expelled from such position into said chamber, said element including an elongated guide piece extending rearwardly therefrom through said first abutment aperture and terminating within the longitudinal bore of said slide member first portion.

3. A toy gun comprising an elongated barrel having a closed forward end, an apertured abutment disposed within said barrel and spaced rearwardly from said forward end to form an elongated chamber, a slide member disposed within said barrel and rearwardly of said abutment and mounted for reciprocation therein, said slide member being actuated rearwardly relative to said barrel to a predetermined cocked position, said slide member, upon reciprocation thereof, effecting entrapping and compressing of a fluid within said barrel intermediate said slide member and said abutment, means for biasing said slide member for relative movement in a forward direction, an element disposed in said chamber for movement intermediate said closed forward end and said abutment, said element being actuated into seating engagement within said abutment aperture upon movement of said slide member into said cocked position and being responsive to the fluid pressure effected by said slide member for movement independently of said slide member from said seated position into said chamber, said element includ-

ing a rearwardly extending guide piece projecting through said abutment aperture and terminating in a sliding connection with said slide member, the length of said guide piece being greater than the longitudinal dimension of said chamber and effecting movement of said element within said chamber along a guided path, and trigger means mounted for releasable engagement with said slide member to retain the latter in said cocked position.

4. A toy gun comprising an elongated barrel having the forward and rear ends thereof closed, a pair of relatively spaced apertured abutments disposed within said barrel, one abutment being spaced from said closed forward end to form an elongated first chamber, the second abutment being spaced from said closed rear end to form an elongated second chamber, the portion of said barrel encompassing said first chamber being provided with an opening, the portion of said barrel encompassing said second chamber being provided with an elongated longitudinally extending slot, a slide member disposed within said barrel and mounted for reciprocatory movement therein, said slide member having a first portion disposed within said second chamber and a second portion disposed intermediate said abutments, said first and second portions of said slide member being movable as a unit, said slide member second portion effecting entrapping and compressing of a fluid within said barrel intermediate said one abutment and the adjacent end of said slide member second portion, spring means cooperating with said slide member for biasing the latter for relative movement in a forward direction, a cocking unit mounted for reciprocatory movement within said second chamber and operable, when moved in a direction toward said closed rear end, from a rest position adjacent said second abutment, to effect simultaneous movement of said slide member in the same direction until the end of said slide member, adjacent the barrel closed rear end, reaches a predetermined cocked position within said second chamber, whereupon said cocking unit is movable independently of said slide member in a forward direction to said rest position, handle means carried by said cocking unit and projecting through said barrel slot to effect actuation of said unit, trigger means mounted for releasable engagement with said slide member to retain the latter in said cocked position, an element, disposed in said first chamber, having a rearwardly extending guide piece projecting through the aperture of said one abutment and terminating in sliding engagement with said slide member second portion wherein said element is actuated by said slide member into seating engagement within said abutment aperture, upon movement of said slide member into said cocked position; said element being responsive to said compressed fluid and suddenly movable independently of said slide member from said seated position into said first chamber, said guide piece cooperating with said slide member second portion to effect movement of said element in a guided path, and safety means operable by said cocking unit, only when the latter is in said rest position, to permit actuation of said trigger means and effect release of said slide member from its cocked position.

5. In a toy gun, an elongate barrel, and apertured abutment disposed within said barrel and spaced rearwardly a predetermined distance from the forward end to form an elongate chamber, a slide member disposed within said barrel rearwardly of said abutment and mounted for reciprocatory movement therein, said member being movable rearwardly relative to said barrel to a predetermined cocked position, an element disposed within said chamber and adapted upon movement of said slide member to said cocked position to be seated within the aperture formed in said abutment, said element being movable independently of said slide member in a path from said seated position toward the forward end of said barrel upon forward movement of said slide member from said cocked position, said element including a

rearwardly extending guide piece projecting through said abutment aperture and terminating in a sliding connection with said slide member, trigger means mounted for releasable engagement with said slide member to selectively retain the latter in said cocked position, and threadably adjustable means for restricting the rearward movement of said slide member whereby the seating of said element within said aperture may be regulated.

6. In a toy gun, an elongated barrel, an abutment disposed within said barrel and spaced a predetermined distance from the rear end thereof, the portion of said barrel intermediate said rear end and said abutment being provided with an elongated longitudinally extending slot having an offset portion, a slide member mounted for reciprocatory movement within said barrel and having at least a portion thereof disposed within said slotted portion of the barrel, a cocking unit mounted for reciprocatory movement within said slotted barrel portion and operable, when moved in a direction toward the rear end of said barrel from a rest position adjacent said abutment, to move said slide member simultaneously therewith in the same direction until a segment of said slide member reaches a predetermined cocked position within said slotted barrel portion, whereupon said unit is movable independently of said slide member in a forward direction to said rest position, trigger means mounted for releasable engagement with said slide member to selectively retain the latter in said cocked position, handle means carried by said cocking unit and projecting through said elongated barrel slot to effect actuation of said unit, an elongated substantially cylindrical sleeve disposed for rotating movement about its axis within said slotted barrel portion and having a slot at least a portion of which is adapted to be substantially aligned with the slot in said barrel, said handle means being reciprocally movable within said thus aligned slots parallel to the axis of said barrel and being radially movable into the offset portion of the slot in said barrel to effect rotation of said sleeve and substantial closing of the slot in said barrel.

7. A toy gun comprising an elongated barrel, an abutment disposed within said barrel and spaced a predetermined distance from the rear end thereof, the portion of said barrel intermediate said rear end and said abutment being provided with an elongated longitudinally extending slot, a slide member mounted for reciprocatory movement within said barrel and having at least a portion thereof disposed within said slotted portion of said barrel, a cocking unit mounted for reciprocatory movement within said slotted barrel portion and operable, when moved in a direction toward the rear end of said barrel from a rest position adjacent said abutment, to move said slide member simultaneously therewith in the same direction until a segment of said slide member reaches a predetermined cocked position within said slotted barrel portion, whereupon said unit is movable independently of said slide member in a forward direction to said rest position, trigger means mounted for releasable engagement with said slide member to retain the latter in said cocked position, handle means carried by said cocking unit and projecting through said elongated barrel slot to effect actuation of said unit, said handle means being adapted to be rotated into the offset portion of said slot when said cocking unit is in said rest position, an elongated substantially cylindrical sleeve disposed within said slotted barrel portion and having an elongated slot within which said handle means may reciprocally move, said cocking unit adapted to slide axially within said sleeve, and said handle means when in the offset portion of said barrel slot being effective to substantially close the remainder of that slot and when in a position outside of the offset portion being effective to substantially align the slot in said sleeve with said barrel slot, whereby said handle means is reciprocally movable within said thus aligned slots.

8. The toy gun recited in claim 2 wherein said second abutment is positioned within said barrel to limit the movement of said slide member in the forward direction, thereby preventing the impact of engagement of the head-piece of said slide member with said first abutment. 5
